UNITED STATES PATENT OFFICE.

WILLIAM E. STEVENS, OF NEW HAVEN, CONNECTICUT, ASSIGNOR TO
SARGENT & CO., OF SAME PLACE.

DESIGN FOR A COFFIN ORNAMENT.

SPECIFICATION forming part of Design No. 17,142, dated February 22, 1887.

Application filed January 13, 1887. Serial No. 224,312. Term of patent 14 years.

To all whom it may concern:

Be it known that I, WILLIAM E. STEVENS, of New Haven, in the county of New Haven and State of Connecticut, have invented a new Design for Coffin Ornaments; and I do hereby declare the following, when taken in connection with accompanying drawing and the letters of reference marked thereon, to be a full, clear, and exact description of the same, and which said drawing constitutes part of this specification, and represents a face view.

This invention relates to a design for emblematical ornament for coffins; and it consists in the configuration and ornamentation, as shown in the accompanying illustration.

The emblem represents an anchor, the shaft of the anchor represented as cylindrical from the head upward to near the cross-bar, where it runs into a polygonal shape. Across the shaft is the representation of a flying banner, on which is a panel for a motto, with the rep-

resentation of tracery extending from behind the banner onto the shaft. The bar is represented as of polygonal shape, its sides ornamented, and from the eye of the bar is the representation of a rope as running downward, coiled about the shaft and head, all as shown in the accompanying illustration. 25

I claim—

The herein-described design for coffin ornament, consisting of the representation of an anchor with a flying banner across the shaft, the representation of tracery extending from behind the banner onto the shaft, and with the representation of a rope as running from the eye downward around the shaft, as shown in the accompanying illustration. 30 35
